UNITED STATES PATENT OFFICE.

WILLIAM MASON, OF NEW HAVEN, CONNECTICUT, ASSIGNOR TO WINCHESTER REPEATING ARMS CO., OF NEW HAVEN, CONNECTICUT, A CORPORATION.

PROCESS OF SWAGING CONOIDAL-END BULLETS.

SPECIFICATION forming part of Letters Patent No. 771,083, dated September 27, 1904.

Application filed April 2, 1904. Serial No. 201,197. (No model.)

To all whom it may concern:

Be it known that I, WILLIAM MASON, of New Haven, in the county of New Haven and State of Connecticut, have invented a new and useful Process of Swaging Conoidal-End Bullets; and I do hereby declare the following, when taken in connection with the accompanying drawings and the numerals of reference marked thereon, to be a full, clear, and exact 10 description of the same, and which said drawings constitute part of this specification, and represent, in—

Figure 1, a view of a soft-metal wire blank formed in accordance with my invention and 15 shown in conjunction with the diagrammatic representation of such a wire rod as it may have been cut from; Fig. 2, a view of one of the forms which a bullet cold-swaged from such a blank may assume; Fig. 3, a view in 20 side elevation of one of the modified forms which the blank may assume; Fig. 4, a corresponding view of another modified form of blank.

My invention relates to an improved process 25 of swaging conoidal-end bullets, the object being to produce a symmetrical conoidal-end bullet free from those objectionable surface imperfections characteristic of bullets now swaged from wire blanks or cast slugs.

With these ends in view my invention consists 30 in a process of swaging conoidal-end bullets consisting in forming a blank having the surface of one end inclined to the longitudinal axis of the blank and then swaging the said end 35 into conoidal form by a properly-shaped die.

In carrying out my invention I place a wire rod 2, of suitable soft bullet metal and diameter, into a cutting-up machine of any approved character and cut it up into blanks of 40 which each is a duplicate of the other and which are produced without any waste of metal. As shown in Figs. 1 and 2, each of these blanks has a cylindrical body portion 3 and corresponding ends 4 4^a, parallel with 45 respect to each other, inclined with respect to the longitudinal axis of the blank, and each consisting of a single surface or cut. These blanks are then cold-swaged into bullet form

by being placed in swaging-dies of any approved character. The shape of these dies 50 will be determined by the particular conoidal form which it is desired to have the bullets assume, which in turn will be determined by the circumstances of use. For illustration I have shown the production of a common form 55 of bullet 5, having a rounded nose 6 and a flat base 7.

By the particular end conformation of my improved blanks I am enabled to swage them so as to produce symmetrical bullets without 60 fins or folds, depressions or protuberances, or other surface imperfections such as have heretofore characterized bullets swaged from wire blanks or cast slugs. Bullets having surface imperfections present a bad appearance 65 and are liable to be rejected on that account. Moreover, every imperfection in the surface of a bullet, whatever the character of the imperfection may be, interferes with the symmetry of the bullet, and therefore with its 70 trajectory and accuracy of flight. Bullets having surface imperfections are also apt to vary in weight and even if initially of the same weight are soon differentiated in weight by the scaling or flaking of their surfaces, all 75 of which tends to decrease their value as accurate projectiles. Theoretically all bullets should conform exactly in shape and weight, so that this factor in the operation of an arm may be constant.

My improved blanks may be used equally well for the production of the so-called "soft" bullets and for the cores of the so-called "jacketed" bullets.

It is not necessary that the ends of the 85 blanks should correspond to each other in form or in inclination. Thus the blank shown by Fig. 3 has its ends 8 and 8^a differentiated from each other, one being sharp and the other blunt, but each consists of a single surface or cut and both are inclined to the longitudinal axis of the blank, which has a cylindrical body portion 9. In the blank shown by Fig. 4 one end has a single cylindrical or concave cut 10, while the other end has a single cylindrical convex cut 10^a, these cuts being inclined 90 95

to the longitudinal axis of the blank, which has a cylindrical body portion 11. I would therefore have it understood that I do not limit myself to the exact form of blank herein shown and described, but hold myself at liberty to make such departures therefrom as fairly fall within the scope of my invention.

Having fully described my invention, what I claim as new, and desire to secure by Letters Patent, is—

A process of swaging conoidal-end bullets which process consists in forming a blank

having the surface of one end inclined to the longitudinal axis of the blank and then swaging the said end into conoidal form by a properly-shaped die.

In testimony whereof I have signed this specification in the presence of two subscribing witnesses.

WILLIAM MASON.
